UNITED STATES PATENT OFFICE.

JOSEPH A. WILLIAMS, OF CLEVELAND, OHIO, ASSIGNOR TO THE WILLIAMS ELECTRIC COMPANY, OF SAME PLACE.

DESIGN FOR A FRAME FOR TELEPHONE-CALLS.

SPECIFICATION forming part of Design No. 32,953, dated July 17, 1900.

Application filed August 21, 1899. Serial No. 728,014. Term of patent 7 years.

To all whom it may concern:

Be it known that I, JOSEPH A. WILLIAMS, a citizen of the United States of America, and resident of Cleveland, in the county of Cuyahoga and State of Ohio, have invented and produced a new and original Design for the Frame of a Telephone-Call, of which the following is a specification, reference being had to the accompanying drawings, forming a part thereof.

In the drawings, Figure I is a perspective view of the frame of the telephone-call. Fig. II is a side elevation.

The design of the aforesaid frame comprises a cylindrical member *a*, terminating at each end in a head *b*. The two heads *b b* are parallel and project, respectively, laterally of all sides of the member *a*. A flat plate or base *c* is arranged parallel with and a distance from the cylindrical member *a*. Base *c* bridges the space between the heads. The

heads *b b* are flanged outwardly, as at *b'*, over the ends of the base *a*, and each flange *b'* terminates in two diverging ears *b² b²*.

The essential and characteristic features of my design consist in the configuration and arrangement of the parts of the frame of a telephone call, so as to form the following: two parallel heads *b b*, connected centrally by a member *a* and arranged at opposite ends, respectively, of a bar *c*, each head terminating at the base in a flange having two ears arranged in a plane parallel with the base.

What I claim is—

The design for the frame of a telephone-call, substantially as shown and described.

Signed by me at Cleveland, Ohio, this 19th day of August, 1899.

JOSEPH A. WILLIAMS.
